UNITED STATES PATENT OFFICE.

OSCAR A. BAUMANN, OF ST. CHARLES, MISSOURI.

BOX-LID FASTENER.

1,100,647.

Specification of Letters Patent. Patented June 16, 1914.

Application filed May 3, 1913. Serial No. 765,308.

To all whom it may concern:

Be it known that I, OSCAR A. BAUMANN, a citizen of the United States, residing at St. Charles, in the county of St. Charles and State of Missouri, have invented certain new and useful Improvements in Box-Lid Fasteners, of which the following is a specification, reference being had therein to the accompanying drawing.

10 This invention relates to a lid or cover locking device for a box and has for its object the production of a lock that can be applied to any box or cover.

Another object of this invention is the 15 production of a lid or cover locking device which cannot become detached from the box or cover, in other words having all the locking members always intact.

With these and other objects in view, this 20 invention consists of certain novel combinations, constructions and arrangements of parts as will be hereinafter fully described and claimed.

In the accompanying drawings: Figure 1 25 is a longitudinal section of a box and cover with the improved locking means mounted thereon. Fig. 2 is an end view of a box with a locking means mounted thereon. Fig. 3 is a view of the opposite end of the box 30 from that of Fig. 2, with the improved locking means mounted thereon. Fig. 4 is a fragmentary section of the bracing cleat of the box, showing the locking hasp and connecting link. Fig. 5 is a fragmentary section 35 of one end of the box with the cover removed. Fig. 6 is a perspective view of an end of the box with the locking device mounted thereon. Fig. 7 is a perspective view of the opposite end of the box as is 40 shown in Fig. 6. Fig. 8 is a perspective view of the locking plate used with this device. Fig. 9 is a perspective view of the connecting link.

Referring to the accompanying drawing 45 by numerals, the box 10 is provided with the ordinary lid or cover 11 which has downwardly projecting flanges 12 at all its edges, said downwardly projecting flanges 12 having an opening formed at 13. Mounted on 50 the rear end of the box is a plate 14 which is provided with a laterally extending foot 15 which is adapted to pass through the opening 13 in the downwardly projecting flange 12 of the cover 11. A bracing cleat 16 is pro-

vided for on this box, and has a pocket 17 55 provided for at its front ends. This pocket 17 is provided with a reduced neck 18 at its upper end. Extending through this reduced neck 18 and into the pocket 17 is one end 20 of a substantially U-shaped locking 60 latch 19, said locking latch 19 having mounted on its end 20 a collar 21 abutting against the lower face of which is a coiled spring 22 which also abuts against a secondary collar 23 at a position lower than that of the collar 21. Threaded on the end of the portion 20 of the locking hasp 19 is a nut 24 which is adapted to be used as means to adjust or regulate the tension of the spring 22. The other end 25 of the locking hasp 19 is positioned within the auxiliary pocket 26 formed in the upper face of the bracing stay 19 adjacent the reduced portion 18 of the pocket 17. A connecting link 27 provided with an engaging loop 28 at one end and a depending 70 portion 29 through which an opening 30 is formed, is connected to the substantially U-shaped locking hasp by means of said opening 30. Connected to the under face of the cover 11 on the opposite end from which the aperture 13 is formed, is a plate 31 that extends beyond the end of the cover and box and is provided with an upwardly extending lug 32 and an aperture 34. The space between the end of the cover 11 and the inner 75 face of the upturned lug 32 is of the same width as the width of the connecting link 27 and is adapted to receive the connecting link 27 when the box is in a locked position. The opening 34 formed in the plate 31 registers 80 with an opening 33 formed in the engaging loop 28 of the connecting link 27 through which a seal is adapted to be placed.

It will be seen from the foregoing description that when the lid or cover of the 95 box is to be locked, the laterally extending foot 15 is placed in the opening 13 in one end of the cover or lid, and the connecting link 19 is brought up over the upwardly extending lug 32 and into the pocket formed 100 by the end of the cover and the lug 32 and is thereby securely held by means of the spring 22 and by the seal.

It is obvious that minor changes may be made in the form and construction of this 105 invention without departing from the spirit thereof. It is therefore not wished to confine the invention to the exact form herein

shown and described, but it is wished to include all such as properly come within the scope claimed.

What is claimed is:

- 5 1. A locking device comprising a substantially U-shaped locking hasp, said locking hasp comprising substantially long and short members extending parallel to each other, collars mounted on said long extension of said locking hasp, a spring positioned between said collars, a nut threaded upon the end of said member of greater length, whereby the tension of said spring may be regulated, a connecting link carried by said locking hasp
10 and provided with an engaging loop at its end, a locking plate provided with an upwardly turned lug at its end to provide a pocket for receiving said loop engaging member of said connecting link, a sealing
15

means passing through said plate and said connecting link, whereby said plate and said connecting link may be held securely together.

2. A locking device comprising a support, a plate adapted to be secured to the top of a box and extend beyond the edge thereof, an upwardly extending flange at the end of said plate, a substantially U-shaped hasp in said support, and a connecting link carried by said hasp adapted to be placed on said plate 25 between the edge of the top of a box and said flange.

In testimony whereof I hereunto affix my signature in presence of two witnesses.

OSCAR A. BAUMANN.
